FOOT PEDAL FOR DICTATING MACHINE

James C. Sturrock, Atlanta, Ga., assignor to
Robert N. Fink, Decatur, Ga.

Filed Mar. 7, 1974, Ser. No. 448,889

Term of patent 14 years

Int. Cl. D13—03

U.S. Cl. D26—13 D

FIG 1

FIG 2

FIG. 3**FIG. 4****FIG. 5**

FIG. 1 is a perspective view of the foot pedal for dictating machine constructed in accordance with our design;

FIG. 2 is a top plan view of the foot pedal for dictating machine shown in FIG. 1;

FIG. 3 is a side elevational view of the foot pedal for dictating machine as shown in FIG. 1;

FIG. 4 is a front elevational view of the foot pedal for dictating machine shown in FIG. 1; and

FIG. 5 is a rear elevational view of the pedal for dictating machine shown in FIG. 1.

The side not shown is a mirror image of the side shown in FIG. 3.

The bottom has no design significance.

I claim:

The ornamental design for a foot pedal for dictating machine, as shown and described.
